UNITED STATES PATENT OFFICE.

WILLIAM C. SHIPHERD, OF CLEVELAND, OHIO.

CLIP KING-BOLT.

SPECIFICATION forming part of Letters Patent No. 316,191, dated April 21, 1885.

Application filed August 26, 1884. (No model.)

To all whom it may concern:

Be it known that I, WILLIAM C. SHIPHERD, of Cleveland, in the county of Cuyahoga and State of Ohio, have invented certain new and 5 useful Improvements in Clip King-Bolts; and I do hereby declare the following to be a full, clear, and exact description of the invention, such as will enable others skilled in the art to which it pertains to make and use the same.

10 My invention relates to improvements in clip king-bolts, the object being to arrange the parts so as to relieve the king-bolt from all lateral strain and to confine the turning of the bolt, and consequently the wear of the 15 same, entirely to the head of the bolt and the engaging part.

With these objects in view my invention consists in certain features of construction and 20 in combination of parts hereinafter described, and pointed out in the claims.

In the accompanying drawings, Figure 1 is 25 an elevation in section of a axle and head-block with my improved clip king-bolt attached. Fig. 2 is a side elevation of the same with the head-block omitted. Fig. 3 is a view in perspective of the king-bolt. Fig. 4 is a view in perspective of the nut-lock. Fig. 5 is a view in perspective of the head-block and 30 perch-plate from the upper side, showing the take-up spring. Fig. 6 is a view in perspective of the nut F.

A and A' represent, respectively, the wood 35 and metal portions of the axle that are embraced by the clip B. The upper portion of the clip is circular in cross-section, and fits into the annular recess c of the part C, and has a central bore that embraces the depending cylindrical part c' of the part C. The clip is provided with the shoulder b, that engages the 40 head of the bolt D, and, when the parts are new, separates the head of the bolt a short distance from the end of the part c'. The bolt D has a square shank that fits into a square hole in the plate C, by means of which the 45 bolt and plate turn together, causing the bolt-head to turn in the clip B. The plate C has a boss, c'', on top, provided with an annular chamber, c'', in which is located the take-up spring E, that surrounds the upper portion of 50 the bolt.

F is a cap-nut that screws onto the end of

the bolt D, and when tightened holds the plate C and the clip B together, and also compresses the spring E into the chamber c'.

G is the nut-lock with a hole, g, adapted to 55 embrace the upper portion of the nut F, and sloping downward on either side so that the ends lie flat on the plate C. Holes g' are provided for securing the part G to the head-block. The nut-lock and contiguous parts 60 are let into the wooden head-block H, and consequently are concealed when the parts are assembled.

I is the spring that is secured to the head-block by the clip J, the screw ends of which 65 pass through the lugs c' of the plate C.

The parts K, projecting laterally from the plate C and integral therewith, are for the attachment of the reach in case a double reach is used. In case a single reach is used there 70 will be but one part K projecting from the center of the plate C, which would necessitate two clips, J, arranged on either side of the center and corresponding lugs c'.

The part C, usually called the "perch-plate," 75 has attached in the usual manner to the outer ends the top portion of the fifth wheel. (Not shown.)

As neither the bolt D nor the nut F are turned in the part C, but remain stationary, 80 it is evident that the wear on the bolt is confined to the head, that on account of its size, thickness, and strength, is adapted to sustain such wear for a long time without material injury. With this construction there is 85 but little strain on the bolt D, the draft being sustained by the interlocking parts of the plate C and clip B.

In actual use, if the bolt D were removed 90 the clip B and plate C would maintain their respective positions under ordinary circumstances on smooth rods.

The take-up spring E keeps the bolt tight 95 against the shoulder b and prevents the parts from rattling.

The socket in the part c' that engages the shank of the bolt is preferably square, but not necessarily, as the shank of the bolt might be made of some irregular shape and the socket made to correspond.

The essential feature is that the bolt shank 100 and socket fit each other and are of such shape,

respectively, that the bolt cannot turn in the socket.

What I claim is—

1. The combination, with a clip having a hollow cylindrical bearing at its upper end and an annular shoulder below said bearing, of the plate having a boss adapted to fit within the cylindrical bearing of the clip, a recess adapted to receive the upper end of the clip, and a recess for the reception of a spring, a bolt the head of which rests against the annular shoulder of the clip, a spring encircling the bolt, and a nut for holding the bolt in position, substantially as set forth.

15 2. The combination, with the plate C, of the

boss c^2 , for re-enforcing the plate and integral with the same, and provided with the annular recess c^3 , forming a seat for the spring E, substantially as set forth.

3. The combination, with a clip king-bolt, 20 of the nut-lock G, and the parts so arranged that the nut-lock is secured to and concealed by the head-block, substantially as set forth.

In testimony whereof I sign this specification, in the presence of two witnesses, this 19th day 25 of July, 1884.

WILLIAM C. SHIPHERD.
